TOY DEVICE

José Ochoa, San Francisco, Calif.

Application October 26, 1939, Serial No. 301,441

11 Claims. (Cl. 280—1.17)

This invention relates to a toy device and more particularly to the type of toy device which may be propelled by manual effort of a rider thereof. The invention is especially related to those types of toy devices which simulate the form of an animal, the natural movement of which is with an undulating motion, such as the jumping of a rabbit, the leap of a deer, or the gallop of a horse.

The object of the invention is to provide a toy device which may be manually operated by a rider to propel the device in a manner simulating the motions of a natural animal. A further object of the invention is to provide a toy device in which rollers on propelling legs are locked at one position but are free to rotate in either direction at another position. A still further object is to provide a toy device simulating a body of an animal and in which the head is movable upwardly and downwardly, and is also movable from side to side for steering purposes.

With the foregoing and other objects in view, all of which will be more apparent as this description proceeds, the invention is exemplified in one form in the novel construction and combination of parts hereinafter described, illustrated in the accompanying drawing, and pointed out in the claims hereto appended, it being understood that various changes in the form, proportion, size and details of construction of the apparatus may be resorted to within the scope of the appended claims without departing from the spirit or sacrificing any of the advantages of the invention.

To more clearly comprehend the invention, reference is directed to the accompanying drawing wherein:

Fig. 1 is a longitudinal vertical section of the device, the head being shown in full, and dot-and-dash lines indicating movement of parts.

Fig. 2 is a plan view of internal mechanism, the body being removed to show mechanical structure.

Fig. 3 is a transverse vertical section on line III—III of Fig. 1, and Fig. 2.

Fig. 4 is an enlarged detail of the lower end of the rear or propelling legs.

Fig. 5 is an enlarged detail of head bracket mechanism.

Referring to the drawing, in which like characters of reference indicate corresponding parts in the several views, 10 is a hollow body, which in this exemplification represents a body of a horse, but it is to be understood that the invention is not limited to the form of a horse but may be equally well employed with other forms of hollow

bodies. The body 10 may be formed of any suitable material which has sufficient rigidity for the purpose, and it may be molded, laminated, or pressed into the desired shape. In the present exemplification, the hollow body comprises a shell having a back portion 11 which mounts a saddle 12. The body has a bottom opening 13 so that the body when loosened from its fastenings 13a may be lifted in its entirety clear of the internal mechanism by means of sliding the body over the head and neck of the horse, the head and neck being small enough to pass through the inclined opening 14 at the forward upper portion of the body. The opening 13 at the under part of the body is closed by a board or base 15 upon which the operative mechanism of the device is supported. At each of its opposite ends the board or base 15 mounts a supporting-frame 16, which preferably comprises a pair of relatively parallel bars which have vertical standard portions 17, 18 at the respective ends joined by longitudinal bar portions 19, the latter also serving as a reinforcement to the back 11 and saddle 12.

Steering roller means are provided, comprising a pair of front legs 20 each of which is supported upon a freely rotating roller 21, the roller being securely fastened to the lower free end of the front legs as by strap plate 22. Each front leg has a vertically disposed pivot pin 23 at its upper end which has pivotal bearing in a vertically disposed housing 24 supported upon the baseboard 15. An antifriction horizontal bearing 25 is interposed between the upper portion of the steering leg and a lug 26 which is connected to the baseboard 15, thus providing for a free and easy axial rotation of the front leg on its vertically disposed pivot 23, for purposes of guiding the device. The guiding of the movement of the device is accomplished by movement of the head 27 from side to side by means of reins 28 held by the rider. It will be noted (see Fig. 1), that the head is pivotally mounted to move from side to side in a horizontal plane and also to move upwardly and downwardly in a vertical plane. Mechanically the head is separated from the hollow body 10, the collar 29 merely serving to cover the severance joint between the head and body. The head has a neck portion 27a, the lower portion of which, where it is adjacent to the body 10, being of substantially the same contour as, but slightly smaller than, the opening 14 so that the opening 14 will readily pass over said neck and head portion. Centrally of its lower face, the neck 27a has a tenon or tongue 30 which is slidable upwardly and downwardly 55

in the clevis 31 of a bifurcated yoke 32 which has pivotal mounting by pin 33 to the apex angle 34 of a two-armed lever 35. Each of the arms of the lever 35 are pivotally connected at 36 to one end of a link lever 37, which has its opposite end fixedly secured to the top of pivot pin 33. Thus by moving the head of the horse from side to side the steering legs are rotatively moved upon their vertical pivots to turn the rollers of both front legs in unison for guiding the device. It will be noted that the weight of the head of the horse is not supported upon this steering means. The head 27 is supported on the forward standards 18 by means of a clamp 38 which engages both of said standards adjacent the top thereof. The clamp 38 has an opening 38a therethrough within which is loosely mounted a headed bolt member 39 which depends downwardly, the lower end of which may be reciprocated forwardly and rearwardly due to the loose pivotal mounting of the bolt at its upper end. The bolt 39 mounts a bracket 40 which is angular in shape, and forms, with the bolt, somewhat of a triangle with the bolt as the hypotenuse, said bracket and bolt being mounted on the clamp 38 to both swing and pivot thereon. The tenon 39 of the head 27 is securely affixed to the upper side of the bracket 40 by suitable means such as screws 41. As heretofore stated, the head is pivotally moved from side to side by means of the reins 28; it is moved upwardly and downwardly by the swinging of the bracket 40 by mechanism hereafter described.

Means are provided for propelling the device in a manner simulating, to a degree, the movement of a natural animal. At each lateral side of the rear end of the baseboard 15 there are depending propelling legs 50 which are mounted for horizontally pivoting on the transverse pivot shaft 51, the ends of which are journaled in bearings 52 mounted on the baseboard 15 by bolts 53. The propelling legs are each rigidly secured at the upper end, as by bolts 54, to an L-shaped treadle lever 55 which extends upwardly from the leg and is turned forwardly of the body to a point substantially underlying the saddle or seat 12 of the driver. At their forward ends, the treadle levers of the respective legs are joined by a cross-bar 56 so that they move upwardly and downwardly in unison. Adjacent said forward end and bar 56 there is mounted suitable means whereby the rider may move the treadle levers 55 upwardly and downwardly, and as herein exemplified comprises stirrup straps 57 which roll upon rollers 58 to prevent wear thereon, a stirrup 59 being provided at the free end. The L-shaped levers 55 are also connected at their rear end by a cross-bar 60 which likewise braces the levers and assures that the levers and the propelling legs on the opposite sides will move in unison. At the lower ends of each of the propelling legs 50 there is a rotatable roller 61 mounted to each propelling leg by an elongated longitudinally curved plate 62, one end of which supports an axle 63 upon which the roller rotates and the other end of which is pivotally mounted as at 64 to the propelling leg. Intermediate the ends of plate 62 it has a sliding fulcrum which is illustrated herein as a pin 65 fixedly secured adjacent the end of the propelling leg and engaged by a slot 66 in the plate 62. With this construction, when the propelling leg is in a forwardly position, the pin 65 is at the rear end of slot 66 and the free end of the leg or hoof is so formed that when the leg is in a forward position the hoof rests

upon the peripheral rim of the roller 61 and serves as a brake against rotation of the roller 61 in either direction. When the lever 55 is pressed downwardly by the rider, the propelling leg 50 is forced rearwardly on the pivot 51. By such movement, the axis of rotation of the roller 63 is shifted from a position forwardly of the pivot 64 and fulcrum pin 65, to a position rearwardly of fulcrum 65, and substantially in vertical alignment with the pivot 64. As a consequence thereof, the pin 65 is moved to the forward end of slot 66 which frees the end or hoof of the propelling leg from its contact with the roller and permits the roller to roll freely in either direction, clockwise or counterclockwise. The force thus imparted propels the device forward on its rollers which are then freely running. The rider may maintain this free running condition by continuing to hold the stirrup down until the device stops rolling. It will be noted that the rider may also hold the treadle levers down with one foot and thus is able to use the other foot to reach the floor and propel the horse rearwardly in order to get it out of corners or to turn it around. A stop means 68 is provided in the path of movement of the treadle lever 55, and it is so arranged and positioned that the downward movement of the lever is limited so that, at the maximum downward stroke of the lever, the axis of rotation of the rollers on the propelling legs will not pass rearwardly of the vertical transverse plane A—A of the pivot 51; thus when the rider takes the weight off of the stirrup and puts his weight more rearwardly upon the saddle, the propelling legs will be thrown forward to their position where they are again locked due to the sliding of the pin 65 to the other end of slot 66 when the roller axis reaches the point forwardly of pivot 64. Although the lever 55 is L-shaped for purposes of mechanical construction, the moment arm of leverage B is from the pivot 51 to the point of attachment of the stirrups adjacent cross-bar 56; and from pivot 51 the force is thence exerted upon the propelling leg. It is preferred that the said moment arm shall be substantially at right angles or perpendicular to the line C from the transverse pivot 51 to the rotative axis 63, since this angle has been found to give an extremely efficient propulsive force to the propelling legs.

In order to reduce the impact of the parts in operation, the stop member 68 may be made of a resilient material, and there may be provided a spring shock-absorbing means 70 which may be clamped as at 71 to the rear standards 17 of the supporting frame, so that on the rebound stroke, the cross-bar 60 comes in contact with the spring shock-absorber 70.

Mounted upon the vertical leg 55a of the lever 55, is a reciprocating rod 72 pivotally connected at one end 74 to a shaft 75, the latter in turn being transversely of and connecting the two levers 55. At its other end, the rod 73 is pivotally connected to the lower end of bolt 39. Therefore, upon the downward movement of lever 55, which moves the vertical lever arm 55a forwardly, the rod 73 will move the end of bolt 39 forwardly, and thus tilt the bracket 40 upwardly thereby raising the horse's head each time the propelling legs are moved rearwardly. It is obvious that upon the upstroke of lever 55, the arm 55a is again moved rearwardly, which returns the head of the horse to its lower, or what may be termed its normal, position. The rod 73 is stabilized against lateral movement at its forward end by operation 75

through a slot in a plate 76 mounted between the upright standards 18 at the forward end of frame 19, and thus prevents the horse's head from wobbling, without preventing it from being moved directly upwardly and downwardly, or turned from side to side on its pivoted bracket. Since there is sliding relationship between the tenon 30 and the clevis 31 of yoke 32, the up and down movement of the horse's head does not interfere in any way with the mechanism which operates to steer the rollers of the front legs.

If desired, the legs may slant outwardly from their mounting on the body to give a broader base and more stability to the toy.

15 It may at times be desirable to have the device freely rotatable without operation of the lever 55 by a rider; for instance, in case a child became fatigued in operating the device and it was necessary to use the device in the nature of a go-cart, or if it is desired to roll the device either forwardly or backwardly when no rider is on it. Such a result may be readily accomplished by means of a latch member 77 having a hooked end 77a which may engage the cross-bar 56 and thus hold lever 55 in downward position against stop 68 whereby the propelling leg is maintained continually in its rearward position and the roller thereof is free to rotate on its axis in either direction.

30 While normally the weight of a child riding the device will return the propelling legs to their forward position when weight upon the lever 55 is released, nevertheless, if desired, suitable springs may be employed to facilitate such operation. Such springs are shown herein as coil springs 78, each of which has one end connected to one of the rear standards 17 and the other end connected to the transverse shaft 75 upon which the reciprocating rod 73 has its pivotal mounting.

40 I claim:

1. A device of the character described comprising a body having a seat for supporting a rider, a pair of depending steering legs having vertically disposed pivotal mounting at one end of said body, a pair of depending propelling legs having a transversely horizontally disposed pivotal mounting at the other end of said body, each of said legs having a rotatable roller at a free end thereof, a rocking lever manually operable for actuating the propelling legs on the transverse pivots from a forwardly position to a rearwardly position, and means for locking the rollers of the propelling legs against rotation at said forwardly position and releasing said rollers for rotation in either direction at said rearward position.

2. A device of the character described comprising a body having a seat for supporting a rider, a pair of depending steering legs having vertically disposed pivotal mounting at one end of said body, a pair of depending propelling legs having a transversely horizontally disposed pivotal mounting at the other end of said body, each of said legs having a rotatable roller at a free end thereof, a rocking lever manually operable for actuating the propelling legs on the transverse pivots from a forwardly position to a rearwardly position, means for locking the rollers of the propelling legs against rotation at said forwardly position and releasing said rollers for rotation in either direction at said rearward position, and stop means in the line of movement of the rocking lever to delimit the movement thereof at a position which prevents the axis of rotation of the rollers of the propelling legs from moving

rearwardly of the transverse vertical plane of the horizontal transverse pivot.

3. A device of the character described comprising a body having a seat for supporting a rider, a pair of depending steering legs each having vertically disposed pivotal mounting at one end of said body, a pair of depending propelling legs having a transversely horizontally disposed pivotal mounting at the other end of said body, each of said legs having a rotatable roller at a free end thereof, a rocking lever manually operable for actuating the propelling legs on the transverse pivots from a forwardly position to a rearwardly position, means for locking the rollers of the propelling legs against rotation at said forwardly position and releasing said rollers for rotation in either direction at said rearward position, a head at one end portion of said body having a pivotal mounting so that the head may be turned to opposite sides of the body, and a linked lever connection between the head and the steering legs whereby the steering legs may be pivotally rotated in unison for guiding the rollers thereof.

4. A device of the character described comprising a body having a seat for supporting a rider, a pair of depending steering legs having vertically disposed pivotal mounting at one end of said body, a pair of depending propelling legs having a transversely horizontally disposed pivotal mounting at the other end of said body, each of said legs having a rotatable roller at a free end thereof, a rocking lever manually operable for actuating the propelling legs on the transverse pivots from a forwardly position to a rearwardly position, means for locking the rollers of the propelling legs against rotation at said forwardly position and releasing said rollers for rotation in either direction at said rearward position, the last mentioned means comprising a plate having one end pivotally mounted on the propelling leg and having the roller journaled therein at its other end and a fulcrum connection with said leg intermediate said plate ends whereby the free end of the propelling leg contacts the tire of the roller at the forwardly position and is released from such contact at the rearward position.

5. A device of the character described comprising a body having a seat for supporting a rider, a pair of depending steering legs having vertically disposed pivotal mounting at one end of said body, a pair of depending propelling legs having a transversely horizontally disposed pivotal mounting at the other end of said body, each of said legs having a rotatable roller at a free end thereof, a rocking lever manually operable for actuating the propelling legs on the transverse pivots from a forwardly position to a rearwardly position, means for locking the rollers of the propelling legs against rotation at said forwardly position and releasing said rollers for rotation in either direction at said rearward position, the last mentioned means comprising a plate having one end pivotally mounted on the propelling leg and having the roller journaled therein at its other end and a fulcrum connection with said leg intermediate said plate ends whereby the free end of the propelling leg contacts the tire of the roller at the forwardly position and is released from such contact at the rearward position, and stop means in the line of movement of the rocking lever to delimit the movement thereof at a position which prevents the axis of rotation of the rollers of the propelling legs from moving

legs from moving rearwardly of the transverse vertical plane of the horizontal transverse pivot.

6. A device of the character described comprising a body having a seat for supporting a rider,

- 5 a pair of depending steering legs having vertically disposed pivotal mounting at one end of said body, a pair of depending propelling legs having a transversely horizontally disposed pivotal mounting at the other end of said body, each of 10 said legs having a rotatable roller at a free end thereof, a rocking lever manually operable for actuating the propelling legs on the transverse pivots from a forwardly position to a rearwardly position, means for locking the rollers of the 15 propelling legs against rotation at said forwardly position and releasing said rollers for rotation in either direction at said rearward position, the last mentioned means comprising a plate having one end pivotally mounted on the propelling leg and having the roller journalled therein at its other end and a fulcrum connection with said leg intermediate said plate ends whereby the free end of the propelling leg contacts the tire of the roller at the forwardly position and is released from such contact at the rearward position, stop means in the line of movement of the rocking lever to delimit the movement thereof at a position which prevents the axis of rotation of the rollers of the propelling 20 legs from moving rearwardly of the transverse vertical plane of the horizontal transverse pivot, a head at one end portion of said body, having a pivotal mounting so that the head may be turned to opposite sides of the body, and a linked lever connection between the head and the steering legs whereby the steering legs may be pivotally rotated in unison for guiding the rollers thereof.

7. A device of the character described comprising a body having a seat for supporting a rider,

- 40 a pair of depending steering legs having vertically disposed pivotal mounting at one end of said body, a pair of depending propelling legs having a transversely horizontally disposed pivotal mounting at the other end of said body, each of 45 said legs having a rotatable roller at a free end thereof, a rocking lever manually operable for actuating the propelling legs on the transverse pivots from a forwardly position to a rearwardly position, means for locking the rollers of the propelling legs against rotation at said forwardly position and releasing said rollers for rotation at 50 the rearwardly position, stop means in the line of movement of the actuating means of the propelling legs to delimit the movement thereof at a position which prevents the axis of rotation of the rollers of the propelling legs from moving 55 rearwardly of the transverse vertical plane of the horizontal transverse pivot, a head at one end of said body having a pivotal mounting so that the head may be turned to opposite sides of the body, and means connecting the head and the steering 60 legs whereby the steering means may be pivotally rotated for guiding the roller thereof.

8. A device of the character described comprising a body having a seat for supporting a rider,

- 70 a pair of depending steering legs having vertically disposed pivotal mounting at one end of said body, a pair of depending propelling legs having a transversely horizontally disposed pivotal mounting at the other end of said body, each of 75 said legs having a rotatable roller at a free end thereof, a rocking lever manually operable for

actuating the propelling legs on the transverse pivots from a forwardly position to a rearwardly position, means for locking the rollers of the propelling legs against rotation at said forwardly position and releasing said rollers for rotation in either direction at said rearward position, the last mentioned means comprising a plate having one end pivotally mounted on the propelling leg and having the roller journalled therein at its other end and a sliding fulcrum 10 connection with said leg intermediate said plate ends whereby the free end of the propelling leg contacts the tire of the roller at the forwardly position and is released from such contact at the rearward position, stop means in the line of 15 movement of the rocking lever to delimit the movement thereof at a position which prevents the axis of rotation of the rollers of the propelling legs from moving rearwardly of the transverse vertical plane of the horizontal transverse pivot, a head at one end portion of said body, having a pivotal mounting so that the head may be turned to opposite sides of the body, and a linked lever connection between the head and the steering legs whereby the steering legs may be pivotally 20 rotated in unison for guiding the rollers thereof.

9. A device of the character described comprising a body having a seat for supporting a rider, steering means having vertically disposed pivotal

- 30 mounting at one end of said body, a pair of depending propelling legs having a transversely horizontally disposed pivotal mounting at the other end of said body, the steering means and propelling legs each having a rotatable roller at a free end thereof, manually operable means for actuating the propelling legs on the transverse pivots from a forwardly position to a rearwardly position, means for locking the rollers of the propelling legs against rotation at said forwardly position and releasing said rollers for rotation at 40 the rearwardly position, stop means in the line of movement of the actuating means of the propelling legs to delimit the movement thereof at a position which prevents the axis of rotation of the rollers of the propelling legs from moving 45 rearwardly of the transverse vertical plane of the horizontal transverse pivot, a head at one end of said body having a pivotal mounting so that the head may be turned to opposite sides of the body, and means connecting the head and the steering 50 legs whereby the steering means may be pivotally rotated for guiding the roller thereof.

10. A device of the character described comprising a body having a seat for supporting a rider, steering means having vertically disposed

- 55 pivotal mounting at one end of said body, a pair of depending propelling legs having a transversely horizontally disposed pivotal mounting at the other end of said body, the steering means and propelling legs each having a rotatable roller at a free end thereof, manually operable means for actuating the propelling legs on the transverse pivots from a forwardly position to a rearwardly position, means for locking the rollers of the propelling legs against rotation at said forwardly position and releasing said rollers for rotation at 60 the rearward position, stop means in the line of movement of the actuating means of the propelling legs for delimiting the movement thereof at a position which prevents the axis of rotation of the rollers of the propelling legs from moving 65 rearwardly of the transverse vertical plane of the horizontal transverse pivot, a head at one end portion of said body having a pivotal mounting so that the head may be turned to opposite sides 70

of the body, and upwardly and downwardly, a lever connection between the head and the steering means whereby the steering means may be pivotally rotated for guiding the device, and means operatively connected to the actuating means of the propelling legs for actuating the movement of the head upwardly and downwardly.

11. A device of the character described comprising a body having a seat for supporting a rider, a pair of depending steering legs having vertically disposed pivotal mounting at one end of said body, a pair of depending propelling legs having a transversely horizontally disposed pivotal mounting at the other end of said body, each of said legs having a rotatable roller at a free end thereof, a rocking lever manually operable for actuating the propelling legs on the transverse pivots from a forwardly position to a rearwardly position, means for locking the rollers of the propelling legs against rotation at said forwardly position and releasing said rollers for rotation in either direction at said rearward position, the last mentioned means comprising a plate having one end pivotally mounted on the propelling leg and having the roller journaled therein at its other end and a sliding fulcrum

connection with said leg intermediate said plate ends whereby the free end of the propelling leg contacts the tire of the roller at the forwardly position and is released from such contact at the rearward position, stop means in the line of movement of the rocking lever to delimit the movement thereof at a position which prevents the axis of rotation of the rollers of the propelling legs from moving rearwardly of the transverse vertical plane of the horizontal transverse pivot, a head at one end portion of said body having a pivotal mounting so that the head may be turned to opposite sides of the body and upwardly and downwardly, a linked lever connection between the head and the steering legs whereby the steering legs may be pivotally rotated in unison for guiding the rollers thereof, and means operatively connected to the rocking lever for actuating the movement of the head upwardly and downwardly, the said rocking lever horizontally transverse pivot and rotative axis of the rollers on the propelling legs being relatively disposed so that the moment arm of the lever is substantially right angular to the line between the said pivot and rotative axis.

JOSÉ OCHOA.
